UNITED STATES PATENT OFFICE

IRA O. BANKS, OF HIGGINSVILLE, MISSOURI, ASSIGNOR OF ONE-HALF TO PAUL R. HEIDBRINK, OF HIGGINSVILLE, MISSOURI

RADIO ANTENNA

Application filed August 22, 1930. Serial No. 477,155.

This invention relates to radio antenna and an object of the invention is to devise a radio antenna which may be housed within a radio with means for effectively controlling 5 the length of the antenna to vary the effective volume and tone of the radio.

Referring to the accompanying drawing which is made a part hereof and on which similar reference characters indicate similar 10 parts,

Figure 1 is a plan view of the device,

Figure 2, a view of the interior of the casing looking in the opposite direction from that seen in Figure 1, and

15 Figure 3, a diagrammatic view of the device.

In the drawing numeral 10 indicates a casing in which the elements are housed. Secured within the casing are posts 11, 12 and 20 13 which are connected by wires to the radio set antenna post, to the ground post on the set and to the outside ground post respectively. Post 12 is connected by means of a wire 14 to a post 21 on which an arm 22 is 25 pivoted, the arm carrying a roller 23 on its outer end for engaging with the resistance element 19 which is built in the form of a coil. One end of the resistance 19 is connected by means of wire 15 with the binding post 13 and the other end of the resistance is 30 connected by means of a wire 17 with a condenser 18. The wire 15 and the condenser 18 are connected by wires 16 and 20 respectively with the antenna post 11. The arm 22 is 35 operated by means of a knob 24 which is connected to the post 21.

In operation the antenna is connected to the radio set as described and as indicated in Figure 3 when the operator wishes to 40 control the length of the antenna he may operate the knob 24 to bring the roller 23 into contact with the antenna 19 at any point desired so as to eliminate as much of the aerial as he chooses. By thus manipulating the dial 45 or knob 24 he may selectively use any length of aerial which he chooses. This gives a wide range of selectivity which is particularly desirable when shifting from stations at greater or less distance from his set. By 50 varying the length of his antenna he may

get a volume and tone control which is impossible with an aerial of a constant length. With a selectivity of say from zero or a few feet up to a maximum of 100 feet or more the operator is able to effectively control the 55 amount of current received by the set. This adjustment, of course, may be instantly made so as to give the operator complete and ready control over the length of his antenna. While the device is not primarily a static 60 eliminator it does give the operator some control over the amount of static in the machine since it enables him to cut down the length of the exposed aerial.

It will be obvious to those skilled in the art 65 that various changes may be made in my device without departing from the spirit of the invention and therefore I do not limit myself to what is shown in the drawing and described in the specification, but only as indicated in the appended claim.

Having thus fully described my said invention, what I claim as new and desire to 70 secure by Letters Patent, is:

An antenna for a radio set comprising a 75 casing having binding posts thereon, the first of said posts being connected to a wire leading to the radio set antenna post, a second having a wire leading to the ground post on the set and a third connected to a wire attached to 80 an outside ground post, the second of said posts being connected in circuit with a fourth post, a movable arm pivotally attached to the last named post, a roller carried by the outer end of said arm, a resistance coil having one end connected to the said third post and having its other end connected through a condenser with the said first post, said roller being in engagement with the said coil, substantially as set forth.

In witness whereof, I have hereunto set my hand at Higginsville, Missouri this 16th day of August, A. D. nineteen hundred and thirty.

IRA O. BANKS.
